UNITED STATES PATENT OFFICE.

CHARLES A. LINDQUIST AND ERIC V. LINDQUIST, OF DES MOINES, IOWA, ASSIGNEES,
BY DIRECT AND MESNE ASSIGNMENTS, TO QUPEE HOSE SUPPORTER COMPANY,
OF EAU CLAIRE, WISCONSIN, A CORPORATION OF WISCONSIN.

HOSE-SUPPORTER.

1,392,776.

Specification of Letters Patent. Patented Oct. 4, 1921.

Application filed January 24, 1920. Serial No. 353,809.

To all whom it may concern:

Be it known that we, CHARLES A. LINDQUIST and ERIC V. LINDQUIST, citizens of the United States of America, and residents of 5 Des Moines, Polk county, Iowa, have invented a new and useful Hose-Supporter, of which the following is a specification.

The object of this invention is to provide an improved construction for hose supporters.

A further object of this invention is to provide an improved hose supporter adapted to be suspended from a garment or in any other suitable manner and provided with 15 means for gripping and securely holding a stocking in such manner as not to tear or otherwise injure even the daintiest fabric.

A further object of this invention is to provide improved hose-gripping means 20 which is simple and cheap of construction, easily attached and detached and adapted to provide a broad and secure grip on the fabric without injury thereto.

Our invention consists in the construction, 25 arrangement and combination of elements hereinafter set forth, pointed out in our claim and illustrated by the accompanying drawing, in which—

Figure 1 is a front elevation of a hose-supporting device embodying our invention. 30 Fig. 2 is a side elevation of the same. Fig. 3 is a front view of the base member of the gripping devices, detached, and Fig. 4 is a similar view of the coacting gripping member.

In the construction of the device as shown a suitable flexible supporting or suspending member is employed which may be formed of fabric, light leather or any other suitable material such as is ordinarily employed 40 for such purpose. The suspending member is in the form of a strap and is so arranged and folded upon itself as to form an upper loop 10, a rear or base loop 11 below said upper loop, and a front loop 12 of less length than and arranged parallel with and in front of said base loop. The front loop 12 and base loop 11 are connected at their upper ends, and separated from the top loop 10, as by parallel rows of cross stitching 13, so that said front loop is free to swing away from the base loop at its lower end at times.

A base plate 14 is provided and is slightly wider than the strap from which the loops 55 are formed and said base plate is secured to

the base loop 11. The base plate 14 preferably is formed with parallel slots 15, 16 adjacent its upper and lower margins respectively, through which the front member of the base loop 11 is passed in sequence, so that said base plate is permitted a sliding movement throughout the length of the loop. Between its upper and lower margins the base plate 14 is formed with an outstanding stud member 17, preferably extending entirely across said plate. At its outer end the stud member 17 is formed with an upwardly extending flange or rib 18 and with a downwardly extending flange or rib 19 of greater length than said flange or rib 18. 70 The flanges or ribs 18, 19 are in the same vertical plane and parallel with the base plate 14. It is to be understood that in the use of the words "upwardly", "downwardly" and the like it is assumed that the device is 75 in normal position of use. The base plate 14 and stud member 17 with its flanges 18, 19 may be formed integrally from metal by stamping and pressing, or may be constructed in any other suitable manner. A clamping member 20 is provided and preferably is formed of a flat plate of metal, or if desired may be bent from wire, or otherwise suitably constructed. The clamping plate or member 20 is formed with a transverse 80 slot 21 adjacent its upper margin and with a relatively wide rectangular opening 22 parallel with, and beneath said slot. The clamping plate 20 is suspended from the forward loop 12 of the supporting strap, 90 said loop passing through the upper slot 21 of said plate. Upward movement of the clamping plate on the loop 12 may be limited by a row of cross stitching 23. The width of the rectangular opening 22 of the 95 clamping plate, vertically, is greater than the width or thickness of the stud member 17 but less than the distance from the upper margin of the upper flange 18 to the lower margin of the lower flange 19 thereof. 100 The length of the clamping plate 20, transversely, is somewhat greater than that of the base plate 14, so that the transverse length of the opening 22 of said clamping plate may be somewhat greater than the transverse length of the stud member 17 and its flanges. The clamping plate 20 is adapted 105 to engage the stud member 17 of the base plate as shown in Figs. 1 and 2. Since the opening 22 of the base plate is of less 110

vertical width than the combined width of the flanges of the stud member, it follows that the operation of engaging or disengaging the clamping plate cannot be effected by straight inward or outward movement of said clamping plate while it remains parallel with the base plate, but that said clamping plate must be oscillated or tilted somewhat to effect either of such operations.

10 For instance to engage the clamping plate with the base plate said clamping plate is grasped between a thumb and finger and tilted outwardly at its upper end and the lower part of said clamping plate is caused to engage over the long lower flange 19. Then the clamping plate is moved upwardly until the lower bar thereof contacts with the lower face of the stud 17, whereupon the upper part of the opening 22 may clear the upper margin of the upper flange 18. Then the upper portion of the clamping plate may be moved toward the base plate, said clamping plate assuming its normal position parallel with the base plate; and the clamping plate may move downwardly slightly until the upper margin of the opening 22 contacts the upper face of the stud member 17. In this position the lower margin of the opening 22 is spaced slightly below the lower face of the stud member 17 but is in a horizontal plane somewhat above the plane of the lower margin of the flange 19.

15 In practical use the parts are assembled as shown and described and the strap supporting member may be suspended by its upper loop 10 in any common or suitable manner as from a garter, corset, supporter waist or other similar member. The clamping member 20 being disengaged from the base plate, the upper portion of a hose or stocking to be supported is laid across the outer end of the stud member and the clamping plate is adjusted to engaging position as previously set forth, portions of the 20 stocking being engaged between stud member 17 and the margins of the opening 22 of the clamping plate and securely held by such engagement. When it is desired to disengage the device the clamping plate is first moved upwardly until the upper margin of the opening 22 clears the upper margin of the top flange 18, then the upper part of the clamping plate is swung outwardly away from the base plate, and the

lower part of said clamping plate is disengaged from the stud member by downward and outward movement away from the lower flange 19.

The base and clamping plates preferably are made relatively broad or long transversely so that a considerable portion of the hose is engaged; but it is to be understood that the device may be of any suitable size, and that any desired number may be used conjointly. The broad gripping surfaces, which preferably are smoothly finished, avoid tearing or undue strain on any portion of the garment, which may thus be securely supported without danger of injury. The integral stud member 17 may be formed so as not to project outwardly a very considerable distance from the base plate, so that undesirable bunching is eliminated.

We claim as our invention—

In a hose supporter having a flexible supporting member formed with depending loops one in front of the other, the outer loop being of less length than the inner loop and having an engaging member formed with a transverse slot, the combination with the longer base loop of a base plate formed of an integral sheet of metal bent and shaped to produce an outstanding stud member transversely arranged and formed at its outer end with upwardly and downwardly extending flanges, the downwardly extending flange being of greater length than the other, said base plate being formed with one transversely arranged slot only in each end portion, the outer portion of the longer base loop being rove through said slots and overlying end portions of said plate, both portions of said loop extending longitudinally of the inner face of the base plate in contacting parallel relations and crossing beneath said stud, said stud being adapted to extend through the slot of the engaging member on the shorter outer loop, whereby the extremities of said loops are adapted to be detachably connected, the stud being wholly separate from and out of contact with the base loop.

Signed at Des Moines, in the county of Polk and State of Iowa, this 3d day of January, 1920.

CHARLES A. LINDQUIST.
ERIC V. LINDQUIST.
